DISPENSING CONTAINER FOR STACKED ELONGATED ARTICLES

Filed April 1, 1948

UNITED STATES PATENT OFFICE

2,577,862

DISPENSING CONTAINER FOR STACKED
ELONGATED ARTICLESCharles Knowlton Shaw, Jr., Pawtucket, R. I.,
assignor to Shaw-Randall Company, Inc., a corporation of Rhode Island

Application April 1, 1948, Serial No. 18,421

2 Claims. (Cl. 312—42)

1

This application relates to a dispensing package for articles of an elongated nature such for instance as a package of shoe laces, although various other articles may of course be packaged and dispensed.

Shoe laces are usually packaged by folding the same in lengths of approximately 4" back and forth upon themselves in pairs, and then banding to hold the folded pairs in assembled relation. These packages are frequently placed in bulk upon a counter or may be displayed in a box or on cards or the like for sale.

One of the objects of this invention is to provide a package in which a given number of bundles or unit pairs of laces or other similar articles may be placed, so that each unit may be easily withdrawn from the package as a sale is made.

Another object of this invention is to provide a package which may afford a display of the merchandise within and yet protect the package from soil.

Another object of this invention is to provide a package in which the articles which are to be dispensed will move by gravity into a position to be withdrawn as one of the articles is taken from the package.

Another object of this invention is to provide a package formed of two members which may be easily put together for assembling the same.

Another object of this invention is to provide a package which may be loaded with the articles to be dispensed and then assembled.

Another object of the invention is to provide a package which may be displayed by hanging the same on a hook upon the wall.

With these and other objects in view, the invention consists of certain novel features which will be more fully described and particularly pointed out in the appended claims.

Figure 1 is a perspective view of the package illustrating a person drawing one of the articles from the package;

Figure 2 is a section on line 2—2 of Figure 1;

Figure 3 is a perspective view of the cover member of the package; and

Figure 4 is a perspective view of the body member of the package.

In proceeding with this invention I provide a body member which serves as a container for the articles. The body member has a back wall with side walls, but no top walls. A second member having both back and front walls as well as side walls is formed to telescope over the body member so as to form a closure for the contents thereof and a complete package which may be

shipped. The cover member is in effect cut away at its lower corners so as to expose the articles, enabling them to be withdrawn from the package, and when the package is in a substantially vertical position the other articles will move by gravity downwardly so that as one is withdrawn a fresh one slides itself into location to be withdrawn.

With reference to the drawings, 10 designates the body member and 11 the cover member, and 12 the article to be dispensed, which in this instance is a package of shoe laces which are folded upon themselves as at 13 and banded as at 14.

The body member 10 has a bottom wall 15 with side walls 16 extending forward from its side edges. These side walls extend short of the end 17 of the bottom wall as at 18, so as to leave the bottom wall protruding beyond the side walls a distance greater than the thickness of the article to be dispensed. Flap 19 is folded in from the back wall 15 as at 20 so as to provide an end closure 21 and is again folded as at 22 so that it may extend into the cover as will hereinafter be explained. Centrally of the end closure 21 25 a tab 23 is cut and raised and provided with an opening 24 so that the package may be suspended from a hook in a vertical position.

The cover 11 comprises a back wall 25 and a front wall 26, while it has side walls 27 extending from edge to edge of the back and front walls so as to provide a generally rectangular tubular construction. The cover also has an end wall 28. The back and front walls extend beyond the side walls 27 a distance substantially equal to the extent that the back wall 15 extends beyond the side wall 16, and thus leaves articles 12 which are positioned in the body exposed at this location when the cover is in place. The front and back walls are also cut away at the location adjacent the end wall 28 as at 20 so as to permit the fingers to easily grasp articles such as 12 which are positioned in the package.

The articles 12 are usually loaded into the body member prior to the positioning of the cover member therein. The cover member 11 is then slid over the body member from the lower edge 17 thereof until the lower edge 17 contacts the wall 28. This cover also telescopes over the flap 19 so that the closure at the upper end 50 of the package is in place. It will, of course, be apparent that the package might be loaded by sliding the cover into position on the body member and then loading the same through the top end with the flap 19 out of position. It will be readily apparent that the articles such as 12

may be grasped by the hands and withdrawn laterally from the package as shown in Figure 1, and that as this is withdrawn from the package, the other articles will all move downwardly by gravity so that the next lower article will take its place.

The cover is usually formed from a single piece of sheet material by folding the stock upon itself at the bottom wall 28 and forming the side walls by flanges overlapping. The cover is of a transparent material, so that the contents of the package may be easily viewed. The flap 19 also serves advantageously for the display of advertising material as indicated at 30.

I claim:

1. An article dispensing package comprising a body member having a back wall with side walls extending therefrom along two of its opposite edges a distance spaced from an end of the back wall, a cover member having back and front walls connected by side walls to telescopingly fit said body member, elongated articles in said body in side-by-side relation and of a dimension substantially the distance between said back and front walls, the back and front walls of said cover member protruding beyond the side walls of the body member in a width less than the length of said article for a distance greater than the lateral dimension of said articles, an end wall connecting said protruding back and front walls, leaving the articles exposed whereby the elongated articles may be withdrawn from the package and a flap extending from the bottom wall of the body member to be tucked into the front

wall of the cover member to serve as a closure for the opposite end of the package.

2. An article dispensing package comprising a body member having a back wall with side walls extending therefrom along two of its opposite edges a distance spaced from an end of the back wall, a cover member having back and front walls connected by side walls to telescopingly fit said body member, elongated articles in said body in side-by-side relation and of a dimension substantially the distance between said back and front walls, the back and front walls of said cover member protruding beyond the side walls of the body member in a width less than the length of said articles for a distance greater than the lateral dimension of said articles, and an end wall connecting said protruding back and front walls, leaving the articles exposed whereby the elongated articles may be withdrawn from the package and means provided at the opposite end of the body member to suspend the same.
